UNITED STATES PATENT OFFICE

RICHARD G. MILLER, OF HUNTINGTON, WEST VIRGINIA, ASSIGNOR TO ROBERTS AND SCHAEFER COMPANY, OF CHICAGO, ILLINOIS, A CORPORATION OF ILLINOIS

PICKING SCREEN

Application filed April 9, 1927. Serial No. 182,265.

My invention relates to improvements in picking screens or coal handling apparatuses whereby the coal or similar material is classified according to size and wherein the various sizes are segregated and fed over picking tables so that they may be separately picked. In the present invention, I provide a picking screen wherein lump, nut and egg coal may all be separately picked, thus enabling the operators to do more satisfactory work or inspection in less time. Other objects will appear from time to time throughout the specification and claims.

My invention is illustrated more or less diagrammatically in the accompanying drawings, wherein:

- Figure 1 is a plan view;
- Figure 2 is a side elevation;
- Figure 3 is a section along the line 3—3 of Figure 1;
- Figure 4 is a section along the line 4—4 of Figure 1;
- Figure 5 is a section along the line 5—5 of Figure 1;
- Figure 6 is a section along the line 6—6 of Figure 1;
- Figure 7 is a section along the line 7—7 of Figure 1;
- Figure 8 is a section along the line 8—8 of Figure 1.

Like parts are indicated by like characters throughout.

A is the working floor of a tipple supported on upright columns A¹ above railroad tracks A² A³ A⁴ upon which are adapted to stand cars A⁵ A⁶ A⁷. A⁸ A⁹ are horizontal parallel tracks on the floor A. Upon these tracks are rollers A¹⁰ A¹¹ which carry the reciprocating screen A¹⁰ which screen has short track sections A¹¹ riding on these rollers. A¹² is a drive head adapted to reciprocate the screen along the track by means of a connection A¹³ and to give the screen a quick reversal at the end of the stroke to feed coal or

other material longitudinally therealong as in the well-known Marcus screen.

B is a feed chute adapted to discharge coal to the upper or receiving end of the screen. The coal passes along this screen as will be described below and may be discharged at the end onto a re-screening conveyor B¹ discharging into a lump and picked run-of-mine loading boom B², thence into the car A⁵ or the coal may be discharged onto a re-screening conveyor B³, thence into an egg loading boom B⁴ into the car A⁶, or into a re-screening conveyor B⁵, thence into a nut and pea loading boom B⁶ and into the car A⁷. B⁷ is a belt or any other suitable type of conveyor arranged beneath the floor A and beneath the screen A¹⁰ and adapted to convey pickings, or rock and bone, or material to be rescreened back to a discharge point B⁸ where rock and bone may be discharged into any suitable receptacle. B¹⁰ B¹⁰ are picking chutes arranged along both sides of the screen adjacent the picking tables so that the pickers may conveniently dispose of the pickings.

At the receiving end the screen has three levels, a lump level C having a lump screen C¹ therein. This lump level extends forwardly along the screen and by a gradual go-down plate C² intermediate the ends, discharges onto the egg level later to be described. Immediately below the lump level is a nut and egg level C³. This level has a nut and egg screen C⁴ through which all sizes smaller than nut and egg fall. Toward the forward end of the nut and egg level is a screen C⁵ through which the nut coal may drop to the nut level C⁶ which is on the same line as the egg level C¹⁶. Extending beneath all the other levels throughout the entire length of the screen and receiving material dropping through the screening surface C³ is the slack level C⁷. Thus there are at the receiving end of the screen three levels, slack, nut and egg, and lump. Immediately thereafter there are four levels, slack, nut, nut and

egg and lump. Later there are three levels, slack, egg and lump, and toward the discharge end only two levels, slack, nut, pea and egg, and lump.

5 On the nut and the egg levels which are in the same plane, there are built integral with the screen and projecting laterally therefrom on either side, wings D, D. Baffle plates D¹ D¹ on the nut level guide the coal on that 10 level laterally outward into the wings D which at this point serve as picking tables for the nut coal. Immediately beyond the baffle plates D¹ D¹, the nut and egg level terminates in a go-down plate D² which 15 conducts the egg coal down to the egg level and immediately adjacent the end of this go-down plate D² are baffle plates D³ D³ which guide the coal from the egg level outwardly on both sides into the wings D, beyond the 20 nut portion of the wings so that the wings at this point serve as egg picking tables. Gates D⁴ D⁴ in the wings discharge into the rescreening conveyor B⁵ and the gates D¹⁴ discharge onto the sideways go-down plates 25 D¹⁷ and thence to the slack level C⁷ so that the nut coal may be discharged before it reaches the egg picking part of the wings D, and a gate D⁵ in the slack level is provided at the same point so that slack may be 30 discharged if desired, or nut can be carried forwardly on level C⁷ by closing gate D¹⁴. Gates D⁶ are provided in the wings D beyond the point where the egg is picked so that the egg coal may be separately discharged to the 35 rescreening conveyor B³ if desired. Otherwise it passes over the go-down plates D¹⁸ at the ends of the wings D to the level C⁷, the inwardly inclinde ends of the wings D⁷ co-operating with the inclined go-down plate to 40 guide the coal inwardly. In order that the coal may be fed outwardly to the wings along the baffles and inwardly to the central portion or level C⁷ of the screen by the elements D⁷, the side wall is cut away. The side wall is 45 cut away for the same reason that the sideways go-down plates D¹⁷ carry nut from wings D. D⁸ is a gate in the nut level C⁶ whereby the nut coal may be dropped out of the system onto the slack level and avoid 50 going through the picking wings D when that is desired.

E is a slack gate in the slack level discharging into a chute E¹ whereby the slack may be fed to a chute or conveyor E² for any desired 55 purpose.

At the end of the lump level is a hinged go-down plate F which eases the lump coal down to the lower level C⁷ at which time before it reaches the loading boom and after picking is 60 complete, it may be mixed with the balance of the coal or any part of the coal carried along level C⁷. The nut coal preferably takes the same course and is normally diverted to level C⁷ so that the lump is not mixed with 65 egg and nut coal after being separated be-

cause if it were, there would be danger of too great degradation.

D¹⁹ D²¹ are baffle plates associated with the baffle plates D¹ and D³. They can be set either in a position parallel with the line of flow when material is deflected equally to the wings on both sides or they may be inclined to one side or another to deflect all the material to the wing on one side or the other. D²² D²³ are re-screening members on the wings 71 D. These screens are provided to finally re-screen the egg and nut on the wings after picking and just before they are delivered onto the booms because under some conditions such re-screening is necessary to take 76 out degradations occurring during the picking and during the travel of the material which would otherwise depreciate the value of the coal.

The use and operation of my invention are 78 as follows:

Coal is fed to the receiving end of the screen by any suitable chute or conveyor discharging thereto. The coal if fed forward by the reciprocating movement of the screen 79 passes over the lump screen. All sizes except lump passes down through the lump screen to a lower level. The lump goes on down the go-down plate onto the lower or egg level and is finally discharged into the re-screening conveyor into the lump loading boom, this being the only boom normally used to load the lump coal. The nut and egg passes forwardly along the nut and egg level, the slack dropping through at first and later the nut dropping through to the nut section, the egg continues on down the go-down plate past the baffles which deflect it to the discharge or egg picking end of the egg picking wings and this egg may be dropped through the gates 80 to the egg loading boom or may be returned to the level C⁷ and moved forwardly and meet the lump coal as it discharges to the rescreening conveyor B¹ and loading boom B². The nut coal which has passed through the 81 nut screen onto the nut level is deflected to the up-stream ends of the picking wings and may there be separately picked. It can be discharged through the gates to the nut and pea loading boom or if the gates are closed 82 will pass on with the egg mixing with it, as the egg picking table is reached and may be handled with the egg in any way desired or may previously be deflected to level C⁷ so as not to interfere with the picking of egg. The slack which is dropped clear through to the bottom level may be discharged directly to the slack conveyor or to a car or any suitable point or may be carried on to the nut and pea loading boom or may be carried on 83 clear to the end of the screen and mixed with the lump, picked egg and nut for run-of-mine or any other combination desired.

The lump will be picked separately, the egg and the nut will be picked also separately at 84

different points along the path of this coal and therefore the operator is enabled to get an effective picked product. By manipulating the various gates, he can get a wide range 5 of groupings of product according to size. He may get lump or run-of-mine. He may get egg alone, nut alone or he may get nut and egg, nut and pea or slack alone depending on the demands of his market, or run-of- 10 mine robbed of all or half of nut or egg or both.

I claim:

1. A reciprocating screen boom having at the feed end, lump and slack levels with 15 between them a nut and egg level and a nut level beneath the nut and egg level at a point removed from the end of the boom, an egg level adapted to receive material from the nut and egg level and also adapted to receive 20 material from the lump level.

2. A reciprocating screen having lump, nut and egg, egg, nut and slack levels, screens one above the other in the lump and nut and egg levels and a screen in the nut and egg 25 level adapted to discharge to the nut level, the nut and egg level having a go-down plate discharging to the egg level, the lump level having a go-down plate discharging to the egg level and deflector plates and side wings 30 associated with the egg level whereby nut and egg are separately discharged to the side wings for picking.

3. In a screen, a central screening portion, picking wings on either side thereof, means 35 in the central screening portion for dividing the coal into two different sizes, means for conducting said sizes separately to different portions of the wings, a gate intermediate the ends of each of the wings whereby under 40 the control of the operator material first placed on the wings may be discharged therefrom or fed along and mixed with the material later placed thereon.

4. In a combined screen and picking table, 45 a picking station at the upstream end of the table, picking wings arranged on opposite sides of the table downstream from the first mentioned picking area, the table having a plurality of decks adapted to lead different 50 sized coal onto the picking wings at different points, deflectors associated with the table for guiding the material to the wings.

5. In a picking and screening table, a lump 55 deck, a slack deck below it, a nut and egg deck intermediate them adjacent the feed end, a nut deck below the nut and egg deck and extending forwardly from a point removed from the feed end, wings on the same level as the nut deck, deflectors on the nut 60 deck to guide material outwardly onto the wings, the nut and egg deck terminating in a go-down plate beyond the deflectors discharging to the nut deck, deflectors on the nut deck beyond the go-down plate adapted 65 to guide material outwardly onto the wings.

6. In a picking and screening table, a lump deck, a slack deck below it, a nut and egg deck intermediate them adjacent the feed end, a nut deck below the nut and egg deck and extending forwardly from a point 70 removed from the feed end, wings on the same level as the nut deck, deflectors on the nut deck to guide material outwardly onto the wings, the nut and egg deck terminating in a go-down plate beyond the deflectors discharging to the nut deck, deflectors on the nut deck beyond the go-down plate adapted 75 to guide material outwardly onto the wings, the lump deck terminating in a go-down plate discharging downwardly to the nut deck beyond the second deflector.

7. In a picking and screening table, a lump deck, a slack deck below it, a nut and egg deck intermediate them adjacent the feed end, a nut deck below the nut and egg deck and extending forwardly from the point removed from the feed end, wings on the same level as the nut deck, deflectors on the nut deck to guide material outwardly onto the wings, the nut and egg deck terminating in a go-down plate beyond the deflectors discharging to the nut deck, deflectors on the nut deck beyond the go-down plate adapted 85 to guide material outwardly onto the wings, the lump deck terminating in a go-down plate discharging downwardly to the nut deck beyond the second deflector. 90

8. In a picking and screening table, a lump deck, a slack deck below it, a nut and egg deck intermediate them adjacent the feed end, a nut deck below the nut and egg deck and extending forwardly from a point removed from the feed end, wings on the same level as the nut deck, deflectors on the nut deck to guide material outwardly onto the wings, the nut and egg deck terminating in a go-down plate beyond the deflectors discharging to the nut deck, deflectors on the nut deck beyond the go-down plate 100 adapted to guide material outwardly onto the wings, the lump deck terminating in a go-down plate discharging downwardly to the nut deck beyond the second deflector, a go-down plate adapted to convey material from the nut deck beyond the point where the lump is discharged to it downwardly toward the slack deck, means in the wings between said deflectors for permitting discharge of material from the screening table. 105

9. In a picking and screening table, a lump deck, a slack deck below it, a nut and egg deck intermediate them adjacent the feed end, a nut deck below the nut and egg deck and extending forwardly from a point removed from the feed end, wings on the same level as the nut deck, deflectors on the 115

nut deck to guide material outwardly onto the wings, the nut and egg deck terminating in a go-down plate beyond the deflectors discharging to the nut deck, deflectors on the nut deck beyond the go-down plate adapted to guide material outwardly onto the wings, means in the wings between said deflectors for permitting discharge of material from the screening table.

¹⁰ Signed at Chicago, county of Cook and State of Illinois, this 28th day of March, 1927.

RICHARD G. MILLER.
